UNITED STATES PATENT OFFICE.

SAMUEL I. BERGER, OF NEWARK, NEW JERSEY.

MECHANICAL TOY.

Application filed May 14, 1925. Serial No. 30,142.

My present invention relates to mechanical toys and more especially to toys representing an animal-propelled vehicle.

It is an object of the invention to provide a toy of the type mentioned, which shall reproduce in an especially realistic manner, the action of a vehicle driven by a balking mule and more particularly which shall simulate the spasmodic jerking action on the reins by the driver, the kicking and balking of the mule, the movement of the vehicle in a changed direction following a balk, all with the use of a spring motor of well known construction, and without the need for complicated actions or transmissions and which toy shall have an easy non-binding action.

In a preferred embodiment of the invention, the draft animal figure is pivoted in thills at a point to the rear of the center of gravity of the figure and connected by reins to the hands of the driver figure which is preferably pivotally seated. The motor beside actuating the driving wheels of the vehicle operates upon a member preferably made of wire, including a rock shaft pivoted to the body of the vehicle and a cranking connection with the axle at its lower end and formed as a tappet or lifter below the legs of the driver figure so that in the action, the driver figure will be flipped rearward by the tappet and through the reins, will cause a balk of the draft animal, which thereafter by gravity action through the reins draws the driver figure back to its original position. Other features of construction hereinafter described contribute to reduction in cost and to ease of assembly.

In the accompanying drawings in which are shown one or more of various possible embodiments of the several features of the invention,

Figure 1 is a side elevation of the toy partly in longitudinal section,

Figure 2 is a plan thereof viewed from the bottom,

Figure 3 is a fragmentary plan of the cart with the driver figure removed,

Figure 4 is a fragmentary side elevation of a modified form of the invention, and

Fig. 5 is a fragmentary perspective view indicating the mount of the pilot wheel bracket.

Referring now to the drawings, I have illustratively shown a vehicle body repre-

senting a milk cart. To the floor of the body 10 is affixed a motor frame 11 carrying the spring motor and having downwardly extending lugs 12 constituting bearing supports for the axle 13 to the free ends 60 of which are rigidly affixed the wheels 14. The vehicle has thills 15 formed of a U-shaped piece of generally rectangular wire near the forward end of which is a cross pin 16 transversely through the animal figure 17 and back of its center of gravity. The cross bar 18 of the thill member extends through an elongated slot 19 in front of cross bar 16, the draft animal figure being, accordingly, by gravity normally biased 70 downwardly at its front legs. Reins 20 through the mouth of the draft animal and through corresponding hooks 21 formed integrally with the stampings of which the draft animal figure is made, extend rearward to the hands of the driver figure 22 which is seated in the cart.

The cart body is preferably formed from a single blank representing a bottom 10, a rear wall 23 tilted upward therefrom, side walls 24 and a footboard 25. The edges of the rear wall and side walls are connected by tangs 26 thereon. The upper edge of the rear and side walls are preferably flanged inward as at 27 to afford solidity of appearance and eliminate free cutting edges. Between the side walls extends a seat member 28 which is preferably formed of a single sheet of metal bent to provide a seat proper, a front 29 and preferably a rearwardly inclined back rest 30, extending through corresponding slits in sidewall flanges 27. The seat member has integral tangs 31 extending laterally therefrom and secured to the side walls of the body, and the bottom of the 95 seat has tongues 32 extending downward through corresponding slits in the bottom and twisted to afford locking connections therewith. The spring motor is of substantially conventional construction and need merely be briefly described. The motor frame is secured to the bottom of the vehicle through tongues 33 extending through corresponding slits therein and twisted as shown for locking coaction. The motor comprises a spring 34 mounted in the frame and adapted to be wound by a key 35 and having concentric therewith a large gear 36 meshing with a pinion 37 laterally thereof, pivoted in the frame and driving a segmental 105

sector gear 38 adapted to mesh as it rotates, alternately with pinion 39 and pinion 40 rigidly mounted on the axle 13.

The driver figure which is preferably of substantially conventional construction is preferably pivotally mounted to the seat of the vehicle. For this purpose, the seat member has up-struck ears 41 spaced by substantially the width of the driver body, the seat of which is interposed between said ears and a pin 42 extending transversely through said ears and through said body affords a pivot mount for the body, which as heretofore noted, is normally retained tilted forward by the tension on the reins 20 exerted by the weight of the draft animal figure.

For moving the driver back and forth, I provide a special tappet member comprising a length of wire, the intermediate portion 43 of which is mounted in ears 44 struck-up from the bottom of the vehicle body, said wire having a downwardly extending U-shaped hook 45 straddling a crank conformation 46 formed in the axle. The upper end of the wire is reversely bent into hook form to provide a horizontal tappet or lifter 47 immediately below the thighs of the driver figure.

It will be noted that there is no linkage between the motor and the driver member, so that the latter will not perform the essentially mechanical movement which in the absence of special precautions will result from such connection. By the action of the mechanism described, the driver is given a sudden flip, which is especially realistic and by reason of the relation of the parts, the action will be relatively sudden and snappy even when the motor is nearly run down, so that through the reins the mule is given a relatively snappy kicking or balking action.

There are further structural improvements in the toy which will now be set forth, and which comprise the construction and assembly of the thills, of the pilot wheel and of the milk cans.

The thills extend along the bottom of the vehicle body adjacent the side walls thereof as shown and pass through corresponding slits 48 in the footboard. They are securely retained without the need for soldering or special handling, against removal by the metal of the seat member 29, the lower edge of which extends into corresponding notches 49 preferably formed at the corresponding parts in the upper edge of the thill member wire. It will be apparent that by this arrangement, the thill construction is securely retained against pulling out of the construction or against pivotal displacement in a vertical or horizontal plane.

The pilot wheel 50 is preferably pivoted on the lower or inwardly turned pivot end of a wire bracket or support 51 which at its upper end is reversely bent into U-form 52

resting upon the floorboard of the vehicle, the open end of the U bracket fitting in a corresponding slot 53 at the bottom of the footboard. The bracket is retained against drawing forward by the lower end of the seat 29 which has notches 54 cut in the lower edge thereof, each straddling one of the legs of the U, the intermediate portion affording accordingly a stop to prevent withdrawal of the cross bar of the U-shaped bracket. 75

The milk can assembly comprises a unitary stamping 55 formed by dies, into generally semi-circular form with individual cylindrical grooves representing the side walls of a succession of milk cans, to which is secured by tangs 56 a second generally flat stamping 57 having embossed thereon, the representations of the covers of milk cans, said stamping superposed over the upper edge of the first blank to complete the semblance of a group of milk cans. The bottom of the first blank is preferably secured as by tangs 58 to the floor of the vehicle. The milk can assembly is disposed immediately to the back of the seat 30 which closes the concave side of the first stamping 55, so that the solid appearance of a group of milk cans is realistically produced. 90

Other features herein disclosed and shown in the drawings need not be described at greater length, as this subject-matter is shown, described and claimed in my copending application, Serial No. 26,608, filed April 29, 1925. Among these features are the conformation of the draft animal with pivoting legs and ears and of the hat of the driver. 95

The operation has been in part set forth hereinbefore and need, therefore, not be set forth at great length. It need merely be noted that as the vehicle moves alternately forward and backward as a result of the operation of the segment gear 38 of the motor and throughout such motion, the rocking of the wire 43 and the upward movement of the tappet or lifter 47 causes the driver figure 22 at intervals to jerk backward and to snap the mule figure upward, whereupon the latter returns by gravity, returning the driver figure to its forward position through tension on reins 20. At the end of a rearward movement of the vehicle when the same suddenly reverses to move forward, the inertia of the rear part of the cart, causes the same to tilt rearward and to raise the thills 15 and mule figure 17 upward, until arrested by the winding key 35 which as noted extends downward. In the slow rotation of the winding key, the same may serve as a pivot about which the vehicle turns, so that the latter may resume operation forwardly in a direction other than that in which the balking had occurred. The construction and operation just described is more fully set forth and claimed 125 130

in my copending application above referred to, as is also the pivoting action of the ears and legs of the draft animal.

It will be noted that the various constructional details set forth make for low cost, ease of assembly, elimination of soldering operations and security and durability of construction.

In another embodiment of the invention 10 shown in a fragmentary view in Fig. 4, the figure 22' of the driver is shown pivoted to the seat of the cart by means of a pivoting tongue 59 soldered, or if desired secured by tangs, to the seat of the driver figure, said 15 tongue extending through a slot 60 in the seat and having an enlargement 61 below the seat to maintain the figure against removal from the seat, but free to pivot forward and backward and to sway slightly 20 laterally. The oscillation of the figure is effected in this embodiment from the pilot wheel 62. For this purpose, a rod 63 is pivoted at its lower end in an aperture 64 near the periphery of the pilot wheel and 25 extends through a corresponding slot 65 in the footboard of the cart into the leg of the driver. The reins 20' are connected to the draft animal figure in the same manner as in the other embodiment.

30 In operation, it will be seen that as the vehicle moves forward or backward, the rotation of the pilot wheel will cause the figure of the driver alternately to be moved back and forth to bring about the corresponding 35 balking action of the draft animal figure. It will also be noted that by reason of the peculiar mount of the driver figure, it may in addition to forward and backward movement, partake of a slight lateral swaying movement which renders the operation quite 40 realistic.

It will thus be seen that there is herein described apparatus in which the several features of this invention are embodied, and 45 which apparatus in its action attains the various objects of the invention and is well suited to meet the requirements of practical use.

As many changes could be made in the 50 above construction and many apparently widely different embodiments of this invention could be made without departing from the scope thereof, it is intended that all matter contained in the above description or 55 shown in the accompanying drawings shall be interpreted as illustrative and not in a limiting sense.

Having thus described my invention, what 60 I claim as new and desire to secure by Letters Patent is:—

1. In a mechanical toy, in combination, a motor driven vehicle having a fixed driver's seat, a figure of a driver pivotally mounted thereto, thills, a figure of a draft animal pivotally mounted near the forward end of the

thills, reins connecting the hands of the driver with the draft animal, and a tappet operated from the motor of the vehicle and arranged periodically to strike the lower part of the legs of the driver to urge the driver 70 backward and thereby cause a balking action of the draft animal.

2. In a mechanical toy, in combination, a motor driven vehicle having a fixed driver's 75 seat, a figure of a driver pivotally mounted thereto, thills, a figure of a draft animal pivotally mounted near the forward end of the thills, reins connecting the hands of the driver with the draft animal figure, and a tappet operated from the motor of the vehicle 80 and arranged periodically to strike the lower part of the legs of the driver to flip the driver backward and thereby cause a balking action of the draft animal, said draft animal figure having excess weight in front of the 85 pivot so that it returns by a gravity action and through the reins restores the driver to initial position.

3. In a mechanical toy, in combination, a 90 vehicle having a spring motor, a seat on said vehicle, ears struck up from said seat, a driver figure having its seat disposed between said ears, a pivot pin through said ears and driver seat for pivotal mount thereof, and means for effecting an oscillation of said 95 driver figure, said means comprising an oscillator member having a rock shaft part mounted in said vehicle frame, an eccentric at one end operated from said axle and a lifter member at the other end engaging the lower side of the leg of the driver, the forward part of said seat being cut away to permit movement of said lifter in the operation of the toy.

4. In a mechanical toy, in combination, a 105 vehicle having a floorboard, a seat having a footboard and road wheels, a pilot wheel, a wire carrying bracket therefor having a U-shaped end extending along said floor board through corresponding apertures in the lower 110 part of said footboard, the open end of said U-shaped support extending through a corresponding slot in the footboard of the seat, the cross bar of said U-shaped support being concealed by said foot board.

5. In a mechanical toy, in combination, a 115 vehicle body including a unitary sheet metal blank comprising a bottom, side walls and an end wall, tangs securing said latter walls together, a motor frame having tangs secured to said bottom, a spring motor in said frame, an axle and wheels thereon, said motor frame having supports for said axle.

6. In a mechanical toy, in combination, a 120 vehicle body having a floor, an axle and wheels, side walls, a seat member having a floor-engaging part, a floorboard extending upward from the forward end of said floor, thills comprising a U-shaped rectangular wire having the free ends thereof extending 125

along the floor-board longitudinally of the vehicle and adjacent the side walls through corresponding slots in the footboard, said seat member extending into and having notches interlocking with corresponding notches in the thill members, whereby the latter are securely retained in position.

7. In a mechanical toy, in combination, a metallic cart comprising a body having a seat, milk cans to the rear of said seat, said milk cans comprising a unitary stamping forming a plurality of contiguous side walls of milk cans and a second unitary stamping forming the tops of said milk cans, and superposed over the upper edge of said first stamping, the rear of said seat closing the opening at the front of the milk can assembly.

8. In a toy vehicle, in combination, a cart

having a seat provided with a back, a representation of a number of milk cans in said cart to the rear of said seat, said milk cans comprising two stampings, one upstanding stamping having a plurality of contiguous generally cylindrical conformations representing the sides of the milk cans, tangs securing said member to the floor of the vehicle, and a second stamping embossed to represent the covers of the various milk cans superposed over the upper edge of said first member, tangs securing said members together, the seat of the vehicle closing the space determined by said side wall and cover members.

Signed at New York city in the county of New York and State of New York this 27th day of April A. D. 1925.

SAMUEL I. BERGER.
